[57] **CLAIM**

The ornamental design for a microwave oven cooking container, as shown and described.

DESCRIPTION

FIG. 1 is an exploded perspective view of a microwave oven cooking container, showing my new design;

FIG. 2 is a left end elevational view thereof;

FIG. 3 is a top plan view thereof;

FIG. 4 is a side elevational view thereof;

FIG. 5 is a bottom plan view thereof;

FIG. 6 is an exploded perspective view of an alternate embodiment of a microwave oven cooking container, showing my new design;

FIG. 7 is a top plan view of the alternate embodiment illustrated in FIG. 6;

FIG. 8 is a front or rear elevational view of the alternate embodiment illustrated in FIG. 6; and

FIG. 9 is a bottom plan view of the alternate embodiment illustrated in FIG. 6; and

FIG. 10 is a right or left side elevational view of the alternate embodiment illustrated in FIG. 6.

FIG.1

FIG. 2
